CLAIM

The ornamental design for a battery charging case for mobile devices, as shown and described.

DESCRIPTION

FIG. 1 is a front side perspective view of the battery charging case for mobile devices.

FIG. 2 is a front view thereof.

FIG. 3 is a back view thereof.

FIG. 4 is a left view thereof.

FIG. 5 is a right view thereof; and,

FIG. 6 is a top view thereof.

The broken lines in the drawings depict portions of the battery charging case for mobile devices that form no part of the claimed design.
